UNITED STATES PATENT OFFICE.

ROBERT H. FENN, OF SUFFERN, NEW YORK.

CALCULATING DEVICE.

980,867.

Specification of Letters Patent.

Patented Jan. 3, 1911.

Application filed April 26, 1910. Serial No. 557,662.

To all whom it may concern:

Be it known that I, ROBERT H. FENN, a citizen of the United States, and a resident of Suffern, in the county of Rockland and State of New York, have invented certain new and useful Improvements in Calculating Devices, of which the following is a specification.

My invention aims to provide certain improvements in calculating devices, especially those of a circular form in which a plurality of annular scales are provided on disks or similar members which are in parallel and contiguous planes, and particularly to that form upon which Letters Patent No. 922,465, dated May 25, 1909, were granted to me.

The accompanying drawings illustrate embodiments of the invention.

Figure 1 shows a plan view with clamp in neutral position. Fig. 2 shows a cross section thereof. Fig. 3 shows a cross section of same with clamp moved toward the left and engaging the upper disk. Fig. 4 shows a cross section of same with clamp moved 25 toward the right and engaging the lower disk. Fig. 5 shows a plan view of clamp. Fig. 6 shows a cross section thereof. Fig. 7 shows an end view of same.

The scales marked upon the device may be the same or similar to those shown in my Letters Patent 922,465, both as to those on the lower opaque disk A, and as to those on the upper transparent disk B. The two disks A and B are also rotatably mounted at the common center of said scales. In Fig. 1 the logarithmic scales L and O and the square root scales are on the lower disk, and the logarithmic scales M and N are on the under surface of the upper disk.

It is extremely desirable and of great usefulness that either a value or a result obtained on the scales of the upper disk, be capable of being transferred to the scales on the lower disk without having to carry this value or result mentally; also that any particular value either on the upper or the lower disk may be marked and the marker fixed for ready reference to the particular value. This is accomplished by my invention.

In Fig. 1, it will be noted that the clamp D is mounted on the central pin P between the two disks A and B, but that it is fixed from motion relatively to the pin only in a direction transversely to itself. The slot S shown in the central portion of the clamp is cut exactly so that its sides engage the pin P

and the index line E continued passes through the center of the pin and consequently through the common center of the two disks. This clamp D is preferably made of some transparent material like celluloid which is also springy or elastic. One end of the clamp D is bent, while hot, upwardly and then back on itself until it is parallel with the surface of the clamp, so that a space F is left between the clamp and the folded over end. This space at the portion of the clamp near the bend is made so that it is slightly less than the thickness of the upper disk, and after a short distance the folded over end has a slight upward offset, so that the space G is a little greater than the thickness of the upper disk. The other end of the clamp is folded downwardly in a similar manner and relatively to the lower disk.

In Figs. 1 and 2 the clamp is shown in the neutral position, that is, the portion of the upper disk where it underlies the folded portion of the clamp occupies a position in the space G which is greater than the thickness of the disk and can therefore be readily turned without engaging or interfering with the clamp, in a similar manner the portion of the lower disk which overlies the folded portion H of the clamp is free to be moved without engaging the clamp, and from the above it is evident that as long as the clamp is maintained in this position relatively to the central pin and to the disks, it may be rotated about the pin without engaging or interfering with either disk; this is an essential detail.

Fig. 3 shows the clamp pushed toward the central pin, the slot S in the clamp allowing this to be done, until the upper disk B enters the space F which is less than the thickness of the disk, this can be done because the material of which the clamp is made is elastic and gives sufficiently to allow the edge of the disk to enter, but is strong and stiff enough to exert considerable pressure, so that the clamp is quite securely clamped or wedged to the upper disk at whatever point may be desired.

Fig. 4 shows the clamp pushed in the opposite direction so that the folded end J engages the lower disk and is held clamped thereto. Thus by a simple push the clamp may be clamped either to the lower or to the upper disk at any point in its circumference. I will now explain several uses of this fea-

ture of my invention. Suppose, for example, it is desired to make a number of different settings in which one value enters in all, in order to avoid the time wasted and trouble of looking this up on any of the various scales of the lower or upper disk for each operation, the clamp is rotated until the index line E registers with this value and then the clamp is pushed in toward the center and clamped to either the upper or lower disk as desired, thus maintaining as long as necessary a mark upon the value being used.

In some solutions of various problems, for example Fig. 1:

15

$$\sqrt{\frac{a^2b}{c^2}} = x$$

in which a, b and c represent numerical values.

20 The index line K on the disk B is placed in register with "a" on the square root scale; the index line E on the clamp D is then brought in register with "c" on the square root scale and then the clamp is pushed in 25 at this point so that it is clamped to the upper disk; then the upper disk B is rotated carrying with it the clamp D until the index line E on the clamp registers with "b" on the scale O, the result X is then read off on 30 the square root scale under the index line K on the upper disk B. Thus it is evident that the clamp can be used to mark a certain point on the upper disk while said disk is being rotated about the central pin, and relatively 35 to the lower disk, and as described above it can be used to transfer a result on the scales of the upper disk to the scales of the lower disk.

It will be noted that the upper disk has a 40 very slight saucer shape with the concavity downward toward the lower disk, the only point of contact being at the lower peripheral edge of the upper disk and the surface of the lower disk where it comes in immediate contact with this edge; this line of contact on the lower disk being between two of the annular scales, any possible wearing of the surface will be immaterial, and thus by this 45 feature any possible wearing of the scales on the surface of the lower disk or of those on the under surface of the upper disk is prevented.

What I claim is:—

1. A calculating device comprising a disk 55 carrying a plurality of annular logarithmic scales, a transparent disk overlying same and having itself a plurality of annular logarithmic scales, the scales on one disk registering with those on the other, said 60 disks being rotatably mounted on a pin at the common center of said scales, and a transparent diametral clamp made of a resilient material slightly longer than the diameter of the lower disk; said clamp being 65 provided with a slot in its central portion,

the pin which fastens the disks together passing through this slot, said slot being of such width as to just allow the pin to be moved in the slot with practically no side to side lost motion; said clamp carrying an 70 index line which coincides with a diameter of the circle forming the boundary of the outer scale on the lower disk, and would if continued pass through the common center of said scales, said slot being cut through 75 said clamp so as to be central of this index line, one end of said clamp being bent upwardly and then folded back parallel to itself with a space between the clamp and the folded portion a little less than the 80 thickness of the upper disk, the end of the folded portion toward the slot, having an upward offset so that the space between it and the clamp body is a little greater than the thickness of the upper disk; the other end of said diametral clamp being bent downwardly and folded back parallel to itself with a space between it and the folded portion a little less than the thickness of the lower disk, the end of the folded portion 90 having a downward offset so that the space between it and the clamp is a little greater than the thickness of the lower disk.

2. A calculating device comprising in combination a lower disk having scales, an upper transparent disk also having scales, a transparent diametral clamp between said disks provided with a slot in its central portion, also an index line coinciding with an imaginary line passing through the center 100 of said slot, one end of said clamp having a hook shaped bend adapted to be clamped over the edge of the upper disk, the other end having a similar hook shaped bend adapted to be clamped over the edge of the 105 lower disk; and a pin passing through the center of the two disks so that the said disks are rotatably mounted, and also passing through said slot in the central portion of said clamp.

3. A calculating device comprising in combination a lower disk having scales, an upper transparent disk also having scales, a transparent diametral clamp between said disks provided with a slot in its central portion, also an index line coinciding with an imaginary line passing through the center 115 of said slot, one end of said clamp having a hook shaped bend adapted to be clamped over the edge of said upper disk, the other end having a similar hook shaped bend adapted to be clamped over the edge of said lower disk; a pin passing through the center 120 of the two disks so that said disks are rotatably mounted, also passing through said slot in the central portion of said clamp, and a cup shaped washer underneath and between the upper head of said pin and the upper surface of said upper disk of some 125 springy material adapted to keep the faces 130

of said disks pressed toward each other with a certain necessary pressure.

4. A calculating device comprising in combination a lower disk having scales, an upper transparent disk having a slight saucer shape, with the concavity downward toward the lower disk, said upper disk also having scales; a transparent diametral clamp between said disk provided with a slot in its central portion, also an index line coinciding with an imaginary line passing through the center of said slot, one end of said clamp having a hook shaped bend adapted to be clamped over the edge of the upper disk, and the other end having a similar hook shaped bend adapted to be clamped over the edge of the lower disk; and a pin passing through the center of the two disks so that the two disks are rotatably mounted, and also pass-

ing through said slot in the central portion 20 of said clamp.

5. A calculating device comprising in combination a lower disk, an upper transparent disk, a transparent clamp between said disks, said clamp being provided with a slot 25 in its central portion, said clamp also having one hook shaped end adapted to engage the upper disk and the other hook shaped end adapted to engage the lower disk, and a pin passing through the center of said disks 30 and also through the slot in said clamp.

Signed at New York in the county of New York and State of New York this 23rd day of April A. D. 1910.
